US0D1030321S

(12) **United States Design Patent** (10) **Patent No.:** **US D1,030,321 S**
(45) **Date of Patent:** **** Jun. 11, 2024**

(54) **COLLAPSIBLE BOX**

(71) Applicant: **In-Store Products Limited,**
Mississauga (CA)

(72) Inventor: **Lambros Karalis**, Toronto (CA)

(73) Assignee: **In-Store Products Limited**,
Mississauga (CA)

(**) Term: **15 Years**

(21) Appl. No.: **29/772,611**

(22) Filed: **Mar. 3, 2021**

(51) LOC (14) Cl. **09-04**

(52) U.S. Cl.

USPC **D3/307**; D3/232; D3/246

CLAIM

The ornamental design for a collapsible box, as shown.

DESCRIPTION

FIG. 1 is an upper perspective view of a collapsible box showing my new design;

FIG. 2 is another upper perspective view of the design of FIG. 1, from a different angle to show additional detail;

FIG. 3 is a lower perspective view of the design of FIG. 1;

FIG. 4 is a side view of the design of FIG. 1;

FIG. 5 is an end view of the design of FIG. 1;

FIG. 6 is a top view of the design of FIG. 1; and,

FIG. 7 is a bottom view of the design of FIG. 1.

1 Claim, 5 Drawing Sheets
